UNITED STATES PATENT OFFICE

JOHN L. BENNETT, OF DECATUR, ILLINOIS, ASSIGNOR TO W. S. MANUFACTURING CORPORATION, OF DECATUR, ILLINOIS, A CORPORATION OF ILLINOIS

FORK

Application filed January 3, 1927. Serial No. 158,582.

This invention relates to improvements in forks. The principal object of the invention is the provision of a fork which may be extended to different lengths and in each length the fork is solid and substantial and securely held.

A further object of the invention is the provision of such a device which is simple in construction, attractive in appearance, cheap to manufacture and easy to operate, and which in all positions is solid and secure and fixed.

A further object of this invention is the provision of an extensible handle for forks or other forms of utensils or the like in which the handle portion is provided of two parts slidable relative to each other, having a plurality of means engaging the two parts and frictionally holding them together, whereby they are fixedly held in an extended or adjusted position.

To the accomplishment of the foregoing and such other objects as may hereinafter appear, this invention consists in the construction, combination and arrangement of parts hereinafter described and then sought to be defined in the appended claims, reference being had to the accompanying drawings forming a part hereof and which show, merely for the purpose of illustrative disclosure, a preferred embodiment of my invention, it being expressly understood, however, that various changes may be made in practice within the scope of the claims without digressing from my inventive idea.

In the drawings—

Figure 1 is a plan view of a device constructed to embody my invention and shown in closed or non-extended position.

Figure 2 is a side elevation of the device shown in Figure 1.

Figure 3 is a longitudinal cross section taken substantially on line 3—3 of Figure 1, the device, however, being shown in an extended position and the forward portion of the extensible member being omitted.

Figure 4 is an enlarged view showing the connection between the handle portion proper and the extensible handle member.

Figure 5 is a cross section taken substantially on line 5—5 of Figure 4.

Figure 6 is a cross section taken substantially on line 6—6 of Figure 4.

Figure 7 is a cross section taken substantially on line 7—7 of Figure 6. 55

Referring now to the drawings the numeral 1 designates the handle portion proper which is preferably in the form of a single piece of wire having its end looped as at 2 to receive the gripping member 3, this gripping member being provided with grooves 4 along its edge to receive the looped portion 2. The handle portion 1 extends forward from the loop in the form of a pair of parallel wires 5 which are suitably secured together at intervals by welding, soldering or similar suitable means. 60

An extensible handle member 6 is provided and is preferably formed of a single piece of wire having the prongs or tines 7 at the forward end. The wire then extends rearwardly in the form of a pair of parallel members 8 suitably secured together at intervals by welding, soldering or similar means and terminating in the upturned or outwardly turned operating lug or finger 9. 70

The extensible member is slidably mounted on the handle member proper 1 for extension purposes, the pair of parallel members 5 and the pair of parallel members 8 being in substantial alignment. Means is provided for holding these two members together in such a way as to permit the extension or movement of one relative to the other, and in the form shown, this means includes a plurality of clasps or clamps 10 which are in the form of a metal strap or ring completely surrounding all of the wires of the two members. These members 10 are 80

fixedly connected to the extensible member 6 by being positioned within the depressed portions 11 of said member 6. It is obvious from an inspection of the drawings that depressions 11 and 13 form bends or bows on the opposite sides of rods 5 and 8. Seats 11' and 13' are provided on each end of the 85

depressions 11 and 13 and form means for preventing clamps 10 and 12 from being displaced. See Figures 3, 4 and 7. They are 90

preferably pressed into this position and into the depressions 11 formed in the wire portions of the member 6 and are pressed around or about the under side of the wire portions of the member 1 so as to tightly but slidably engage said member 1. This connection is made in such a way as to cause the depressed portions 11 of the member 6 to engage the top surfaces of the member 1 and increase the frictional engagement afforded by this connection. It is provided in the form disclosed nearer the rear or handle end of the device.

At the forward or fork end of the device a similar construction is provided but in this the parts are reversed. The clamp members 12 are of similar construction but are fixedly secured to the forward end of the handle member 1 by being pressed or forced into the depressions 13 formed in the outer end of the handle member 1 and preferably from the under side of the handle member 1. These depressions cause the wire parts of handle member 1 to be forced inwardly and to frictionally engage the adjoining wire parts of the extensible member 6 and the clamp or ring member 12 thus afford a frictional but slidable connection between these two parts.

It is therefore seen that in the form shown the frictional clamping means is fixedly secured at one end to the extensible member and at the other end to the stationary or handle member and that the extensible member with the fixedly attached clamping means 10 slides on the handle member 1, the parallel wire members 8 sliding through the clamping member 12 fixedly secured to the forward end of the handle member 1. The extending movement of the parts is limited by the arrangement of clamping means and the depressed portions of the members 1 and 6, for as the nearest clamping means approach engagement, the friction is increased due to the curved formation of the wire members and the extending movement limited when the curved portions come into engagement with each other. At this point the friction has been considerably increased, so that the frictional engagement between the parts is greater and the parts are, therefore, more securely held in this position. It is to be noted that even in this position there is a considerable overlapping of the two members 1 and 6, whereby the handle as a whole is of sufficient strength to accomplish its various purposes, and the structure as a whole is not weakened by providing for the extensibility of the device.

In the less extended positions it is to be noted that the members 1 and 6 are parallel to each other and that the distance between the different groups of clamping members 10 and 12 is substantial so that the bracing effect is greater. Furthermore, at the ex-

treme rearward or closed position the upturned finger or lug 9 engages the gripping member 3 and thus forms a stop for the rearward or closing movement of the device.

It is also to be noted that when the parts are in their closed or non-extended position the clamping member 10 to the left in Figures 1 and 2 is positioned at the beginning of the loop 2 of the main handle member 1, and the parts cannot be moved further in that direction because the divergent sides of the loops will not permit the passage of said clamping member 10.

The clamping and frictional construction shown and provided by the different groups of means results in a very secure connection between the two parts of the device in any adjusted position, and the overlapping arrangement of the two members 1 and 6 results in a bracing and supporting construction for the device when in its various extended positions.

The gripping member 3 may be provided of wood, composition or other suitable material, which preferably does not conduct heat. This is shaped to afford a convenient and comfortable grip.

While I have described and disclosed this construction as applicable to a fork, it is to be understood that it may be applicable to other forms of utensils and the like.

What I claim is:—

1. A device of the character described including, in combination, a main handle member, an extensible handle member, a clamping member fixedly secured to said extensible member near its rear end and slidably and frictionally engaging said main handle member, and a clamping member fixedly secured to the forward end of said main handle member and slidably and frictionally engaging said extensible handle member whereby said extensible handle member may be moved on said main member and frictionally held in different adjusted positions, said clamping members being fixedly connected to their handle members by forming said handle members with depressed portions within which said clamping members fit.

2. A device of the character described including, in combination, a main handle member, an extensible handle member, a clamping member fixedly secured to said extensible member near its rear end and slidably and frictionally engaging said main handle member, and a clamping member fixedly secured to the forward end of said main handle member and slidably and frictionally engaging said extensible handle member whereby said extensible handle member may be moved on said main member and frictionally held in different adjusted positions, said clamping members being fixedly connected to their handle members by forming said handle members with depressed portions within

which said clamping members fit, said depressed portions of each handle member forming bends or bows on the opposite side which engage the other handle member.

5 3. A handle construction for a utensil and the like including a main handle member formed of a piece of wire and having an extended portion provided by parts of the wire extending substantially parallel to each other, 10 an extensible member formed of a single piece of wire and having a handle portion formed by two parts of wire extending substantially parallel to each other and positioned adjacent said first-mentioned handle member, a plurality of clamping means fixedly secured to each of said members and slidably and frictionally engaging the other of said members, whereby the two members may be extended relative to each other, and 15 securely held by frictional engagement in an adjusted position.

4. A handle construction for a utensil and the like including a main handle member formed of a piece of wire and provided with 25 a gripping portion, the handle portion being provided by parts of the wire extending in engagement with each other, an extensible member formed of a single piece of wire and also having a handle portion formed by two 30 parts of wire extending in engagement with each other and positioned adjacent said first-mentioned handle member, a plurality of clamping means fixedly secured to each of said members and slidably and frictionally 35 engaging the other of said members, whereby the two members may be extended relative to each other, and securely held by frictional engagement in an adjusted position, said extensible member having means adapted to 40 engage the gripping portion of the handle member to limit the rearward movement of the same.

5. A device of the character described including, in combination, a main handle member composed of a single piece of wire and provided with an elongated handle portion formed of a pair of substantially parallel wire strands, an extensible member formed of a single piece of wire and having an elongated portion provided by a pair of substantially parallel wire strands overlying said 50 first-mentioned elongated handle portion, and means connected to one end of said main handle member and frictionally and slidably engaging said extensible handle member, and another means connected to one end of said extensible handle member and frictionally and slidably engaging said main handle member whereby said extensible handle member 55 may be moved relatively to said main handle member and held in different positions thereon.

6. A handle construction for a utensil and the like composed of two parts, one part being provided with a gripping portion and

having extended parallel portions closely associated to mutually brace each other, the other handle part also having extended parallel portions closely associated to mutually brace each other, said extended parallel portions of the handle parts being positioned in alignment and in contact with each other for a substantial portion of their length when in non-extended position, said handle parts being formed with seats and clamping elements positioned in said seats and frictionally engaging the other handle parts, whereby said handle parts may be adjusted longitudinally with relation to each other and frictionally held in their adjusted positions. 70

7. A handle construction for a utensil and the like composed of two parts, one part being provided with a gripping portion and having extended parallel portions closely associated to mutually brace each other, the other handle part also having extended parallel portions closely associated to mutually brace each other, said extended parallel portions of the handle parts being positioned in alignment and in contact with each other for a substantial portion of their length when in non-extended position, said handle parts being formed with depressions and seats in said depressions and clamping elements positioned in said seats of said depressions and frictionally engaging the other handle parts, whereby said handle parts may be adjusted longitudinally with relation to each other and frictionally held in their adjusted positions. 80

In testimony that I claim the foregoing, I have hereunto set my hand this 27th day of December, 1926.

JOHN L. BENNETT.

CERTIFICATE OF CORRECTION.

Patent No. 1,837,751.

Granted December 22, 1931, to

JOHN L. BENNETT.

It is hereby certified that the name of the assignee in the above numbered patent was erroneously described and specified as "W. S. Manufacturing Corporation", whereas said name should have been described and specified as U. S. Manufacturing Corporation, as shown by the records of assignments in this office; page 2, line 9, before the word "member" insert the word handle; and that the said Letters Patent should be read with these corrections therein that the same may conform to the record of the case in the Patent Office.

Signed and sealed this 16th day of February, A. D. 1932.

(Seal)

**M. J. Moore,
Acting Commissioner of Patents.**
